UNITED STATES PATENT OFFICE.

CHARLES S. BURTON, OF OAK PARK, ILLINOIS.

CONTAINER FOR MUSIC ROLLS AND THE LIKE.

Application filed August 9, 1920, Serial No. 402,275. Renewed August 16, 1923.

The purpose of this invention is to provide an improved container for music rolls and the like, particularly designed and adapted to permit the contents to be withdrawn from the end of the container without removing the container itself from a pile of like containers in which it may be situated; and to permit also the withdrawal of the container from the pile when so desired, instead of withdrawing the contents from the container. It consists in the elements and features of construction shown and described, as indicated in the claims.

In the drawings:

15 Figure 1 is a vertical longitudinal section of a container embodying this invention, showing a music roll contained therein.

20 Figure 2 is a similar view showing the closure withdrawn for removing the contents, and the music roll therein partly expelled prior to its removal by hand.

Figure 3 is a horizontal longitudinal section, showing the container closed and the roll therein.

25 Figure 4 is a detail section of the lower forward corner of the device with parts in closed position, but with the catch released and the closure not yet withdrawn.

Figures 5 and 6 are plan views of the two 30 members.

Figure 7 is a section at the line, 7-7, on Figure 5.

In the structure shown in the drawings, 1 represents a tubular container having a 35 closed end and an open end. 2 is the closure for the open end adapted to telescope therewith and being open-topped for withdrawal of the contents from the container when the closure has been first withdrawn and tilted to a position shown in Figure 2. 3 is a 40 check strap for limiting the withdrawal of the closure from the container, the same consisting of flexible material lying upon the inner or upper side of the bottom of the closure and container respectively, and having its ends secured to said parts respectively by being threaded down through slits, as at 1^b and 2^b, in the container and closure respectively, and folded back and glued down upon the under side of the bottom of said parts respectively, as seen at 3^a and 3^b, in respect to the closure and container respectively. The length of the check strap is such as to prevent the closure from being withdrawn farther than so that the rear edge

of the bottom, 2^a, of said closure still remains lodged upon the forward corner of the bottom, 1^a, of the outer member, 1, of the container. 4 is a spring positioned against the rear closed end of the outer member, 1, 60 of the container for yieldingly thrusting the roll, 5, forward for expelling it to a position at which its forward end may be taken hold of by the user for completely withdrawing it, as seen in Figure 2. 6 and 7 are 65 two members of the catch device for engaging the closure, 2, with the outer member, 1, of the container at closed roll-containing position. The catch member, 7, is a thin metal plate secured preferably near its rear 70 edge upon the under side of the bottom, 1^a, of the outer member, 1, of the container, having its forward edge provided with a slight recess or notch, 6^a, occupying only a portion of the width of said forward edge, 75 and leaving projecting the remaining portion of said edge as seen at 6^b, for the purpose of engagement with the engaging lip of the catch member, 7. Said catch member, 7, is made of a piece of sheet material 80 preferably of such length that its ends may be folded up at 7^a, and so that when said ends are thus up bent, it fits snugly in the open end of the container member, 1, said 85 up-bent ends reinforcing the corner bearing against the vertical sides of said container member, 1, affording means of securing the catch member, 7, firmly to the container as indicated by the rivet eyelets, 8. For the purpose of rendering this catch member 90 rigid,—that is, so that it will be prevented from springing up between the ends, and so that it will thus reinforce the stiffness of the bottom of the container member, 1, and also to form a catch lip for it, the strip of 95 which it is made is slotted transversely from the rear edge nearly three-quarters of its width, as indicated by the edges, 7^b, and the portion, 7^c, between said width is folded 100 downward and then wrapped back and up over around the body of the strip so as to make said body consist of three thicknesses throughout the portion of its length between the three slits, the forward edge of said 105 folded and wrapped central portion, 7^c, projecting beyond the first mentioned fold so as to overhang a short distance as seen at 7^d to constitute a lip for the engagement of the projections, 6^b, 6^b, of the catch member, 6. Preferably said catch member, 6, is of 110

spring material and normally bent or sprung so as to have the form seen in Figure 2 with its forward edge with the engaging projections, 6^b, extending off below the bottom of 5 the closure member, 2, but adapted to be sprung up by proper pressure properly applied, practically flat against the under side of said closure bottom to pass over the three-ply bar of the catch member, 7, adapted 10 and ready to spring down behind and be engaged under the lip, 7^a, of said catch member. For disengaging the catch member, 6, from the catch member, 7, and also for withdrawing the container from the pile, as hereinafter explained, there is provided a lug 15 strap, 9, secured back of the forward engaging edge of the catch member, 6, as may be done conveniently by the same rivet eyelet, 9^a, which secures said catch member, 6, to the closure bottom, and extending thence 20 forward along under said catch member, 6, and up through the recess or notch at 6^a, and past the lower forward corner of the closure so as to protrude for engagement by 25 the fingers of the operator for withdrawal of the container from the pile, and also for disengaging the said catch member, 6, from the catch member, 7, as will now be explained.

30 When the music roll is contained in the container as seen in Figure 1 and the user desires to get it for use, he will press with his thumb against the forward end of the closure at the lower part thereof, thereby 35 forcing back the closure sufficiently to disengage the engaged lip, 6^b and 7^a, of the catch member which will be understood as being held in secure engagement by the forward thrust of the spring, 4, operating 40 against the roll, 5, the latter pressing against the forward end of the closure. Simultaneously with thus pressing rearwardly with the thumb, the operator will engage the lug strap, 9, between thumb and finger and 45 lift slightly, thereby first, by means of said lug, holding the catch member, 6, up so that if it is a spring, as shown, it will not remain down on the bottom of the container member, 1, as seen in Figure 1, while the closure 50 is being lifted a slight amount which it can be lifted by reason of its height being less than the interior height of the outer member, 1, as indicated by the crevice shown at 55 10 in Figure 1, and, secondly, lifting the closure itself to take up the amount of clearance shown at the crevice, 10. Upon this lifting, the spring, 4, reacting to thrust the roll against the forward end of the closure, tends to thrust the closure forward, and the 60 operator yielding to the pressure which his thumb will feel, and releasing the closure the roll will be protruded, and the closure will be tilted down as seen in Figure 2, whereupon he may withdraw the roll completely. When the catch member, 6, is a

spring as shown, the operation as above described causes the lug strap, 9, to tend to draw the free end of said catch member, 6, up toward the under side of the closure; and it is possible to construct the device with 70 said catch member with a spring of such tension that it may be thus pulled up flat against the under side of the closure so as to permit the closure to be thrust out by the reaction of the spring, 4, without regard to the 75 loose fit of the closure in the outer member, 1, as indicated by the crevice, 10, and even though parts may be so closely fitted that no such crevice may appear.

It will be understood from the foregoing 80 description that upon returning the roll to the container while the closure remains protruded down at open position as shown at Figure 2, the operator upon swinging the closure up to horizontal position and pushing it inward will thrust the roll back and the catch member, 6, will be re-engaged with the catch member, 7, automatically, even though the catch member, 6, is not a 85 spring, but somewhat more readily and surely if it is a spring as described. When this catch member is not a spring, the engagement is assured by the operator pressing upon the upper part of the forward closed 90 end of the closure member, or at least as far up as the middle part against which the hub of the roll engages, because this insures the closure being tilted downward slightly, or affected with a slightly downward tilting 95 tendency, by reason of the elastic forward thrust of the roll against said forward end of the closure which in such slight tilting 100 action fulcrums over the point of pressure of the operator's finger thereupon, the pressure of the roll against the inner side of the closure end being slightly below such point of pressure of the finger and thus tending to hold the closure downward against the bottom of the container, and insuring the engagement of the two catch members with 105 each other.

I claim:

1. In a container for music rolls or the like, a tubular outer member having a closed end and an open end, an open-topped closure adapted to telescope in the open end of the outer member; a catch member mounted on the bottom of the closure consisting of a thin strip having its forward end recessed over part of its width to leave the end edge protruding over the remainder of said width; a co-operating catch member mounted on the inner side of the bottom of the outer member of the container, said co-operating catch member having a thin slightly protruding edge spaced slightly up from said bottom for engagement under said protruding portions which form the catch-edge of the first mentioned catch member; a lug strap secured at a point from which it 115 120 125 130

may extend from the under side of the first mentioned catch member through the recess in the front edge thereof and forward to protrude for manual engagement at the 5 front end of the closure, and a spring in the rear end of the outer member of the container for yieldingly thrusting the music roll forward against the forward end of the closure to yieldingly hold the two catch 10 members in engagement.

2. In the construction defined in claim 1, the second mentioned catch member extending across the entire width of the outer member of the container, and having its ends 15 upwardly bent and secured to the vertical sides of the container outer member for reinforcing the corners of said outer member.

3. In the construction defined in claim 1, said second mentioned catch member being 20 made of sheet metal strips slotted at two transverse lines from its rear edge forwardly partly across its width and having the part between said slits folded downwardly and further wrapped around the 25 body of the strips and terminating at the upper side projecting rearwardly for forming the engaging lip of said catch member.

4. In the construction defined in claim 1 30 a check strap to limit the withdrawal of the closure member, said check strap being at the upper side of the bottom of the container, and attached by the engagement of its ends in transverse slits in the bottoms 35 respectively, of the container outer member and the closure and folded up against the under side of said bottoms respectively secured thereto.

5. A container for music rolls and the like 40 consisting of a tubular outer member having a closed end and an open end; an open-top closure member adapted to telescope in the open end of the outer member; co-operating catch members, one mounted on the bottom 45 of the outer member having an inwardly or rearwardly projecting engaging lip, and the other mounted on the bottom of the closure member having a forwardly or outwardly projecting lip for engaging the inwardly or rearwardly projecting lip of the other member; and a lug adapted to be 50 pulled for withdrawing the closure connected thereto at a point from which it may extend forwardly of the first mentioned catch member and protrude for manual engagement at the front end of the closure, and means operating on the closure member 55 when at content-enclosing position for yieldingly urging said closure member in opening direction to hold the catch members in engagement, whereby withdrawal of the closure member to open position, may be effected by pressing the closure member inwardly against said yielding means and simultaneously pulling upon the lug.

6. A container comprising an outer tubu-

lar member having an open end; an open top closure member telescoped into said open end member; co-operating catches on the inner side of the tubular member and the outer side of the closure member projecting 70 for engagement with each other respectively forwardly or outwardly and rearwardly or inwardly with respect to the container; a lug for withdrawing the closure member secured to the bottom of the same and extending out under the catch member of the closure, and a check strap for limiting the withdrawal of the closure member extending along the upper side of the bottom of the container and attached by the engagement 80 of its ends in transverse slits in the bottoms respectively of the container outer member and the closure, and folded up against the under side of said bottoms respectively and secured thereto.

7. A construction of the character indicated consisting of a tubular outer member having an open end; a closure member adapted to telescope in the open end of the outer member, means for withdrawing the closure member; and a check strap for limiting its withdrawal extending along the 90 under side of the bottom of the container outer member and attached by engagement of its ends in transverse slots in the bottoms 95 respectively of the container outer member and the closure and folded up against the under sides of said bottoms respectively and secured thereto.

8. A container of the character indicated 100 consisting of a tubular outer member having an open end, a closure having an inwardly open end adapted to telescope in the open end of the outer member, and co-operating catch members, one mounted on the 105 inner sides of the bottom of the outer member having an inwardly or rearwardly projecting lip normally overhanging and spaced upwardly from said bottom, the other mounted on the under side of the bottom of the closure member having a forwardly or inwardly projecting lip normally spaced downwardly from said bottom for engaging under the upwardly spaced lip of the 110 first mentioned catch.

9. A container for music rolls and the like, consisting of a tubular outer member having an open end; an open-topped closure member adapted to telescope in the open end of an outer member; co-operating catch members, one mounted on the bottom of the outer member having an inwardly or rearwardly projecting lip and the other mounted on the bottom of the closure member having a forwardly or outwardly projecting lip for engaging under the rearwardly projecting lip of the other catch member; means for causing such engagement when the closure member has been 120 telescoped into closing position in the 125

tubular member; a lug adapted to be pulled for withdrawing the closure member, connected thereto at a point from which it may extend under and forwardly of the first mentioned catch member and over the second mentioned catch member so as to be tucked under the latter by the operation of the

means for engaging the lip of the catch of the closure member under the lip of the catch of the outer member.

In testimony whereof, I have hereunto set my hand at Chicago, Illinois, this 3d day of May, 1920.

CHARLES S. BURTON.
